UNITED STATES PATENT OFFICE.

JOHN L. REMLINGER, OF PROVIDENCE, RHODE ISLAND.

DESIGN FOR A JEWEL-HOLDER.

SPECIFICATION forming part of Design No. 19,375, dated October 22, 1889.

Application filed August 17, 1889. Serial No. 321,150. Term of patent 7 years.

To all whom it may concern:

Be it known that I, JOHN L. REMLINGER, a citizen of the United States, residing at Providence, in the county of Providence and State 5 of Rhode Island, have invented and produced a new and original Design for Jewel-Holders, of which the following is a specification, reference being had to the accompanying drawings, forming part thereof.

10 Figure 1 is a view of a jewel-holder showing my design. Fig. 2 is a front view, and Fig. 3 a side view, of one of the prongs, these three views being deemed necessary to fully illustrate my design.

15 The leading feature of my design consists in the curved (usually termed "ogee") form of the prongs.

In the drawings, A is the base, B B are the prongs, and C is the jewel. The prongs B are 20 tapering, the base D being of larger cross-section than the upper end E. The lower half of the prongs is formed convex on the outside and concave on the inside, while the upper half is concave on the outside and convex on

the inside, the outer surface forming the convex lower half F and the concave upper half G, as is shown in Fig. 3. The prongs are also curved sidewise, as is shown in Fig. 2, the lower half being formed convex on one side and concave on the opposite side, while the 25 upper half is concave on the side where the lower half is convex, and the opposite side of the upper half is convex, the convex and concave lines intersecting and forming the line of beauty. All the outlines of the tapering 30 prongs have this line of beauty or curved line, the extremities of which turn in different directions. The point H projects over the jewel.

Having thus described my new and original design, what I claim is—

The design for a jewel-holder herein shown and described.

JOHN L. REMLINGER.
